Inventor:

UNITED STATES PATENT OFFICE.

HUGH BENJAMIN LINDSEY, OF ORCHARDS, WASHINGTON.

BALANCE-STAFF FOR WATCHES.

1,202,075.

Specification of Letters Patent. Patented Oct. 24, 1916.

Application filed January 3, 1916. Serial No. 70,084.

To all whom it may concern:

Be it known that I, HUGH BENJAMIN LINDSEY, a citizen of the United States, residing in Orchards, in the county of Clarke, 5 in the State of Washington, have invented new and useful Improvements in Balance-Staffs for Watches, of which the following is a specification.

My invention relates to staffs on which the 10 balance wheels of watches are mounted.

The object of my invention is to produce a staff for the balance wheels of watches made of separable parts and which may be of different sizes and designs for interchangeable 15 use in the repair and replacement of such parts.

To these ends my invention includes the combination and arrangement of component parts to be hereinafter described and more 20 particularly pointed out in the claim.

In the accompanying drawings, in which like characters indicate similar parts, Figure 1 is an elevation of my balance staff, and Fig. 2 is a similar view showing parts thereof 25 in cross section.

My invention includes, generally, a staff or spindle having a thickened lower portion, a projecting screw-threaded stem, a hub loosely carried on said stem and a cap 30 screwed upon the outer end of the stem, adapted to clamp the hub between its lower face and the thickened portion of the staff.

Referring now to the drawings, 1 indicates my spindle or staff having the projecting 35 screw-threaded stem 2, and as shown by the drawings, is provided with a beveled shoulder 3 at the point from which the stem extends from the staff. Loosely carried upon said stem is provided the hub 4 having a cut- 40 away portion 5 and annular shoulder 6 adjacent to its upper end, upon which may be mounted a balance wheel. Said hub is centrally bored and adjacent to each end of the

bore is provided with cupped portions 7 and 8 adapted to register with the shoulders on 45 the staff 1 and cap 9, respectively.

As shown in the drawings, the hub 4 is clamped upon the stem 2 by the cap 9 screwed upon the outer end of the stem and provided with the projecting and beveled lips 10, 50 which register with the cupped portion 8 of the hub and are coincident in size and shape therewith, the cap being adapted, when the cap is screwed tightly upon the stem, to clamp the hub rigidly in position on the staff. 55 The staff of my invention, when thus assembled, is inserted in its proper place in the structure of a watch, and it will be appreciated that if injury occurs to any of the parts or to the balance wheel carried thereon, 60 the cap may be readily removed and the parts conveniently disassembled or replaced by similar parts which may be carried in the stock of a watch maker, without any inconvenience to the watch maker or injury to the 65 delicate parts of the watch that are required to be removed.

Having thus described my invention, what I claim as new and desire to be secured by Letters Patent is—

A balance staff for watches, comprising a spindle having a trunnion at one end and a screw-threaded stem integral therewith, a shoulder on the spindle intermediate of its ends, a smooth bored hub loosely carried 75 on the stem having a cupped portion surrounding each end of the central bore, a screw-threaded cap comprising a trunnion carried thereon and a projecting shoulder on the cap surrounding its center bore adapted to rigidly secure the hub on the stem, said shoulder on the spindle and shoulder on the cap coinciding with the cupped portions of the hub, substantially as described.

HUGH BENJAMIN LINDSEY.
